UNITED STATES PATENT OFFICE

170,303

TABLET ARMCHAIR OR THE LIKE

David Chapman, Chicago, Ill., and Richard G. Reineman, Muskegon, Mich., assignors to The Brunswick-Balke-Collender Company, Chicago, Ill., a corporation of Delaware

Application February 13, 1953, Serial No. 23,614

Term of patent 14 years

(Cl. D15—8)

To all whom it may concern:

Be it known that we, David Chapman and Richard G. Reineman, citizens of the United States, residing at Chicago, in the county of Cook, State of Illinois, and Muskegon, in the county of Muskegon, States of Michigan, respectively, have invented a new, original, and ornamental Design for a Tablet Armchair or the like, of which the following is a specification, reference being had to the accompanying drawing, forming a part thereof.

In the drawing:

Fig. 1 is a perspective view of a tablet armchair or the like, showing our new design.

Fig. 2 is a top plan view thereof.

The dominant features of our design are shown in full lines.

We claim:

The ornamental design for a tablet armchair or the like, as shown and described.

DAVID CHAPMAN.
RICHARD G. REINEMAN.
